UNITED STATES PATENT OFFICE

ARTHUR F. HALL, OF PHILADELPHIA, PENNSYLVANIA, ASSIGNOR TO HALL ARCH COMPANY, OF PHILADELPHIA, PENNSYLVANIA, A CORPORATION OF DELAWARE

FURNACE

Application filed September 15, 1927. Serial No. 219,647.

My invention relates to improvements in furnaces, furnace walls and the like and it has for its object to provide an improved furnace and an improved furnace wall construction.

Another object of my invention is to provide an improved furnace wall built up from molded block units and comprising inner and outer wall sections that are interlocked in spaced apart relationship so that they mutually support each other and provide an air space between them through which air is forced and then delivered in a pre-heated state to the furnace as in my co-pending application Serial Number 108,969, filed April 4, 1927.

The invention resides in certain features of construction and mode of operation set forth in the following description, the several novel features thereof being particularly pointed out and defined in the claims at the close of the description.

In the accompanying drawings:—

Figure 1 is an elevation of a portion of a furnace wall constructed in accordance with my invention.

Figure 2 is a view in horizontal section on line 2—2 of Fig. 1.

Figure 3 is a view in vertical section on line 3—3 of Fig. 1.

Figures 4, 5 and 6 are details of one of the two kinds of blocks constituting the outer wall section of my improved construction.

Figure 7 is a detail of the locking pin hereinabove described.

Figure 8 is a sectional plan view of a portion of a furnace wall constructed in accordance with my invention, but differing in some respects from the wall shown in Figs. 1 and 2.

Figure 9 is a perspective view illustrating a feature of the wall shown in Fig. 8 and is hereinafter more fully described.

Figure 10 is a vertical sectional view on the line 10 of Fig. 8, including also a portion of the floor of the furnace.

Figure 11 is a plan view of one of the floor blocks hereinafter described.

Figures 12, 13 and 14 are details hereinafter described.

My present invention is herein shown as embodied in an oil burning furnace, like that shown and described in my prior application referred to but it will be obvious to those skilled in this art that it is not limited in this respect and may be embodied in furnaces of other kinds. It may be constructed, as in that application, with side, front and rear walls and in the case of an oil burning furnace, said front wall may be provided with a burner port and cone or register, as usual.

The present construction is characterized by the provision of an air space 8 within, and throughout the extent of, the wall of the furnace. This air space is provided by building the wall in two sections comprising an outer wall section 13 and an inner wall section 12, and it is an important feature of the invention that the inner wall section 12 is made from molded blocks of carborundum or any other suitable material having high thermal conductivity, the necessary tensile strength and a high resistance to fusion, while the outer wall section 13 is built up from blocks of molded diatomaceous earth (kieselguhr) or any other suitable refractory material having low thermal conductivity and high heat insulating property. The two materials mentioned, however, viz, carborundum for the inner wall section and diatomaceous earth for the outer wall section, I regard as preferable as they give to said two sections the desired characteristics to a high degree.

As explained in my prior application, above referred to, air is forced through the air space 8 of the wall under pressure from an inlet at one end of that air space and, after traversing the latter is delivered into the furnace to support combustion from the opposite end thereof. It will, therefore, be clear that as the air passes through the wall it is heated by the in-

5 inner carborundum wall section 12 which is exposed to the flames of the furnace, and is therefore delivered into the furnace in a pre-heated state thereby increasing the efficiency of the furnace beyond that obtained when the furnace is supplied with air that is not pre-heated.

10 The inner wall section 12 is constructed from blocks 14 of carborundum or the like, laid on edge in tiers but staggered so as to break the vertical joints between them, each vertical joint of each course being positioned midway of the block immediately above it and midway of the block immediately below it.

15 At each corner of the furnace the two adjacent inner wall sections are constituted in part, and connected, by a single tier of L-shaped block units 15, of carborundum, which are common to both of said inner sections.

20 Alternate blocks of this corner tier occupy positions that are the reverse of the other blocks of the tier thus interlocking the two inner wall sections.

25 The outer wall section 13 is constructed from block units 16 of diatomaceous earth or the like laid on edge in tiers, but staggered so as to break the vertical joints, each vertical joint of each course being positioned midway of the block intermediately above it and midway of the block immediately below it. At each corner of the furnace the two adjacent outer wall sections are constituted in part and connected by a single tier of L-shaped block units 17 which are common to both sections, alternate ones of which occupy reversed positions relatively to the others.

30 Each block unit 14 is of rectangular or oblong shape except that at its middle, and upon its inner or air space side, it is made with a perpendicular lug 14^a extending from top to bottom of the block. Thus each block unit 14 is of symmetrical T-shape in plan, the body of the block constituting the head of the T and the lug the stem thereof. The body of the block may conveniently be made one or two inches thick, for example, 4½ inches wide and 9 inches long. The body portion of each block 16 will have the same width and length as the body of block 14 and its thickness may be as desired, or the same as that of the block 14, viz, 2 inches, for example. Each block unit 16 is of symmetrical U-shape in plan being provided at its opposite ends, and upon its inner or air space side, with perpendicular lugs 17^a extending from the top to the bottom of the block as indicated in Fig. 4. It follows that when the two sections of the wall are built up from these T-shaped and U-shaped block units, the lugs of one section register vertically and interlock with the lugs of the other, the several vertical series of registering lugs providing a multiplicity of vertical and parallel air channels. The lugs 14^a and 16^a are preferably all of one length and in setting up the two wall sections the latter

are spaced apart, or separated a distance that is substantially greater than the length of the lugs thereby providing ample, or capacious, passage-ways or ducts 19 between the ends of the lugs and the opposite wall section, said ducts connecting the vertical parallel air channels just referred to and providing a multiplicity of passage-ways for the air at opposite sides of each vertical air channel, those at one side of said channel being offset laterally relatively to those at the opposite side. From the above description it will be apparent that the air passing through the wall on its way to the interior of the furnace will impinge upon and pass around the lugs 14^a and 16^a thereby being caused to travel a sinuous course which not only thoroughly agitates the air, but brings it into very intimate contact with the heated carborundum blocks 14, the provision of the lugs 14^a on the air space sides of the latter giving to each block a surface area for contact with the air much greater than would be the case with a flat sided carborundum block.

35 A feature of my present invention consists in providing an intermediate layer of cushioning and heat insulating material such as asbestos mill board 20^a, or the like, between the outer steel casing 20 and the wall.

40 The blocks 16 and 17 of the outer wall section, or some of them, are secured, or fastened, near their middle by bolts 21 to the outer casing. The head of each bolt 21 is outermost and its shank extends through the steel casing 20, the intermediate cushioning layer 20^a, and block 16, to approximately the inner side of the latter where its threaded inner end is provided with a nut 21^b. The nut 21^a is hexagonal and occupies a hexagonal pocket 21^c upon the inner side of the block and fits the latter sufficiently to be held thereby against rotation so that the bolt is tightened up by application of a wrench to its outer end.

45 The outer steel casing 20 with the intermediate cushioning layer 20^a serves to protect the outer wall and to reinforce the furnace structure against the injurious effects of vibration. Also the intermediate layer 20^a serves to insulate the wall structure from the outer steel casing against the transmission of heat and vibrations from one to the other.

50 The blocks 16 of the outer wall section are molded from diatomaceous earth but any other suitable material of low heat conductivity may be employed if desired, and a novel feature of the construction of these blocks consists in providing each with a suitable reinforcing and strengthening core or skeleton 22 of suitable material such as manganese steel. This skeleton 22, Figs. 4, 5 and 6, is shown as 55 made with transverse end bars 22^a extending into the end lugs 16^a and the block is provided with semi-circular grooves 22^b, one at each side of each lug, and near the extremity thereof. The lug 14^a of each carborundum block 14 60

- is molded near its extremity, and at opposite sides thereof, with semi-circular grooves 14^a which register with the grooves 22^a of the lugs 16^a immediately above and below it, thereby 5 co-operating with the latter to provide passages for pins 23 which positively lock the lugs together. These locking pins are flanged at their opposite ends, said flanges serving to hold the pins against accidental displacement. 10 Preferably the pins 23 are molded from carborundum but they may be made from manganese steel or any other suitable material. In Figs. 8 and 10 the end terminals 22^b of the skeleton frames 22 are disposed upon the ends 15 of the lugs of the block and extend transversely from the top to the bottom thereof. Thus when two blocks 16 are placed end to end the end terminal sockets 22^b register and provide a round hole between the blocks for the reception 20 of an articulated locking rod made up of short sections 24 pivotally connected together by pintles 24^a. The lugs 14^a of the carborundum blocks 14' constituting the inner wall section of the structure illustrated in Figs. 8 and 25 10, are molded with round vertical holes 14^b through them that register with the holes provided by the socket terminals 22^b and receive the articulated rod made up of sections 24. Thus the articulated rod serves as a key to lock 30 the lugs of the two wall sections together. The articulated rod loosely fits its holes and sockets and by raising it upwardly any one or more of the carborundum blocks normally held by it may be removed when it is necessary to substitute a new one. The rod 24 is preferably, 35 though not essentially, made sectional as described for the reason that in some cases the space above the furnace is so limited that a one-piece locking rod could not be lifted far enough. By making the rod in sections pivotally connected together as described it is flexible laterally and its sections can be folded sidewise as they are raised out of the wall thus permitting removal of the rod in situations 40 where the overhead space is very limited. 45 The end bars 22^c of the metal skeleton reinforcing frames 22 are made at their outer ends, that is, the ends thereof adjacent the outer face of the block, with corner terminal bars 22^c extending from the top side of the block to its bottom side, the corner bars 22^c of each block 16 fitting against the adjacent corner bars 22^c of the two blocks at the opposite ends thereof as shown in Figs. 2 and 8. 50 At the middle of each metal reinforcing skeleton 22 there is provided an anchor bolt socket 22^e providing a hole through the block 16 extending from its inner to its outer face. This hole is equipped with a lining or bushing 22^g made from the same material as the asbestos mill board lining 20^a for the casing 20, or any other suitable material of low heat conductivity. The pocket 21^c, Fig. 5, for the nut 21^b, Fig. 7, being the enlarged inner end 55 60 65 of this hole. As will be observed from Figs. 2, 5 and 7 the inner end of lining 22^g is flanged to provide a seat for the nut 21^b of bolt 21. In this way the nut and shank of the bolt 21 are well insulated from the metal skeleton frame 22 so that comparatively little heat is transmitted from the latter to the bolt. 70 Upon the top and under sides of the outer ends of the sockets 22^c of each metal skeleton reinforcement 22 are provided lugs 22^f, Figs. 1, 2, 4 and 6, whose outer faces, together with the outer end of socket 22^c, are flush with the outer face of the block, and these lugs 22^f, which are twice as wide as the corner reinforcing bars or terminals 22^c, each register, as shown in Fig. 1, with the two end corner bars 22^c that are above or below it, as the case may be. It will thus be observed that when the wall is constructed the weight of the upper blocks 16 is supported or sustained by the metal reinforcement thus relieving the frail body of diatomaceous earth of each block of injurious strains and stresses. It will also be observed that the end corner bars 22^c protect and reinforce said body adjacent said corners and the ends. 80 85 90 95 100 105 110 115 120 125 130
- If desired provision may be had for positive interlocking engagement between the metal reinforcing frames of the blocks 16, and this may be effected, as illustrated in Figs. 12, 13 and 14, by providing the upper ends of the corner bars 22^c and of the upper lug 22^f with studs 33 and 36, respectively, and the lower ends of said corner bars and of the lower lug 22^f, with sockets 34 and 35, respectively. Thus, when the blocks 16 are assembled in a wall the two lugs 33 at the opposite ends of each block 16 will be paired with the lugs 33 at the abutting ends of the two adjacent blocks and each pair of lugs 33 will occupy the socket 35 of the block immediately above them as indicated in Fig. 12. Also, at each pair of abutting ends of the blocks 16 two of the sockets 34 will be registered side by side and provide a recess or notch for the reception of the lug 36 of the block 16 immediately below said abutting ends. 120
- Figure 13 illustrates a modified form of reinforcing metal frame wherein the ends of the bar 20^b, instead of being provided with the sockets 22^a of Figs. 2, 3 and 6, are formed with exposed terminal lugs 37 to occupy the semi-circular grooves 14^a of the carborundum blocks immediately above and below the bar 22^b. 115
- The longer side of each corner blocks 17, Fig. 2, measures the same in length and width (or height) as the outer side of the block 16 while the shorter side of said corner block is half the length of the longer side. The metal reinforcing skeleton 22' of each corner block 17 is constructed substantially the same as the frames 22 of the blocks 16 except that it is of angular shape as shown in Fig. 2 and is provided with three exposed corner reinforcing and protecting bars 22^c and the an-

chor bolt socket 22^a thereof is located at the middle of the longer side of the frame.

With the construction shown in Fig. 2 the two relatively perpendicular parts of the outer wall section are connected at the corner of the structure only by the tier of corner blocks 17 which intermesh with the blocks 16 of said two parts. In Figs. 8 and 9 I have illustrated a construction wherein the end lugs of the two vertical rows of main blocks 16' of the two parts of the wall which intermesh with the opposite sides of the tier of corner blocks 17', are directly intermeshed and positively interlocked by means of cross-shaped pins 26, Fig. 9. With this construction, the blocks 16' which are interlocked by the cross-pins 26 are each provided with a skeleton frame 22 provided at one end with a cross-bar 22^b made at its ends with socket terminals 22^c like the socket terminals 22^d of Fig. 2 and it will be clear that in the assembled wall of Fig. 8 the socket members 22^d of each block lug so constructed will be disposed at right angles to the socket members of the two block lugs above and below it so that the cross locking pins 26 that are placed in the sockets of each lug and its two neighbors, serve to positively lock said lugs together.

As shown in Fig. 10 the outside casing 20 is carried under the floor of the furnace and forms part of the latter. This floor also includes a bottom or lower layer of blocks 27 which may be made from fire clay, diatomaceous earth, or other suitable material. Preferably diatomaceous earth is used for these blocks and in this case each is provided with a reinforcing and metal skeleton 28, preferably made from the same material as the frames 22 and 22'. The skeleton frame 28 is made at each corner of the block 27 with a prop 30 to rest upon the casing 20. These props 30 are embedded in legs formed upon the block 27, one at each corner thereof, and these legs serve to provide an air space between the casing 20 and the blocks 27 through which some of the air that is forced through the walls passes from the air space of one wall to the air space of the opposite wall. The blocks 27 support a layer of blocks 31 arranged on edge, said blocks being made from any suitable heat insulating material such as diatomaceous earth, fire clay or the like. Upon the top of the blocks 32 of carborundum, or other suitable material having high resistance to fusion.

A furnace constructed in either of the above described manners has great endurance or life and strength, it has great resistance to injury through vibration, the loss of heat units through radiation is very small if not practically wholly eliminated and the efficiency of the furnace is relatively great because of the fact that, as in my application above noted, the air that is supplied to the furnace is first pre-heated by travelling

through the air space of the furnace wall. It will also be clear that while the air is travelling through the vertical wall or walls of the furnace it repeatedly impinges upon and passes around the lugs of the inner carborundum blocks and, therefore, is thoroughly agitated and heated by the latter. Furthermore, there are no dead air spaces or pockets within the wall to trap and hold bodies of air.

The blocks of both the inner and outer wall sections are set up with cement between them and as in my application referred to the abutting sides and ends of the blocks may be grooved or channeled to provide pockets to hold bodies of cement which serve as keys to lock the blocks against relative horizontal movement laterally.

After each block 16, or 16', is placed in position and fastened there by means of its anchor bolt 21, the pocket 21^c, Fig. 5, is filled in around and over the nut 21^b, Figs. 2 and 3, with body 50 of plastic diatomaceous earth or other suitable material having low thermal conductivity of heat.

What I claim is:—

1. A block unit for walls consisting of a molded body of refractory heat insulating material and a reinforcing metal skeleton embedded in said body, said skeleton being made with bars disposed at the surface of said body and constituting corners of the block.

2. A block unit for walls consisting of a molded body of refractory heat insulating material and a reinforcing metal skeleton embedded in said body made at its opposite ends with vertical bars disposed at the surface of said body and constituting the outer end corners of the block.

3. A block unit for walls consisting of a molded body of refractory heat insulating material and a reinforcing metal skeleton embedded in said body made at its opposite ends and at its middle with portions thereof that extend to the top and bottom side surfaces of the block to register with the corresponding parts of the frames of other blocks when incorporated in a wall whereby the load borne by the block is sustained by its metal skeleton reinforcing frame.

4. A block unit for walls consisting of a molded body of refractory heat insulating material and a reinforcing metal skeleton embedded in said body made at its opposite ends and at its middle with vertical bars disposed at the outer surface of said body and with said end bars constituting the outer end corners of the block, said vertical bars being provided at their opposite ends with studs and sockets, respectively, to interlock with the studs and sockets of other blocks in courses above and below the same when the block is incorporated in a wall.

5. A block unit for walls consisting of a molded body of refractory heat insulating

material and a reinforcing metal skeleton embedded in said body made at its opposite ends with vertical bars disposed at the surface of said body and constituting the outer 5 end corners thereof, and made near its middle with an anchor bolt socket.

6. A block unit constructed in accordance with claim 5 wherein said anchor bolt socket is tubular, and including also a tubular lining for said tubular socket made from a non-metallic material of low heat conductivity.

7. A U-shaped block unit for walls consisting of a molded body of refractory heat insulating material and a reinforcing metal skeleton embedded in said body made at its opposite ends with exposed socket terminals constituting parts of the lugs of the block and adapted to be occupied by locking elements whereby said lugs are connected with the lugs of other blocks.

8. A wall constituted by molded block units and comprising inner and outer wall sections occupying spaced apart relationship to provide an air space between them; vertical rows 25 of lugs upon the inner sides of both wall sections integral with the blocks thereof, the lugs of each vertical row of the outer wall section being intermeshed with the lugs of one of the vertical rows of the inner wall section with the end of each lug of each wall section spaced away from the opposite wall section to provide a capacious air passage between the two, and a vertically disposed rod locking the lugs of each vertical row to the 30 lugs with which they intermesh.

9. A wall constructed in accordance with claim 8 wherein said rod is made up of pivotally connected sections and is removable by endwise movement thereof.

10. A wall built up from molded block units and comprising inner and outer wall sections spaced apart relatively to provide an air space between them, the blocks of 40 said outer wall section being made from diatomaceous earth and the blocks of the inner wall section being made from carborundum or the like; metallic reinforcing means incorporated in the outer wall section, and vertical rows of lugs upon the inner sides of both wall sections integral with the blocks thereof, the lugs of each vertical row of the outer wall section being intermeshed with the lugs of one 45 of the vertical rows of the inner wall section with the end of each lug of each wall section spaced away from the opposite wall section to provide a capacious air passage between the two.

11. A wall built up from molded block units and comprising inner and outer wall 50 sections spaced apart relatively to provide an air space between them, the blocks of said outer wall section being made from diatomaceous earth and the blocks of the inner wall section being made from carborundum or the like; metallic reinforcing means incorporated

in the outer wall section; vertical rows of lugs upon the inner sides of both wall sections integral with the blocks thereof, the lugs of each vertical row of the outer wall section being intermeshed with the lugs of one of the 70 vertical rows of the inner wall section with the end of each lug of each wall section spaced away from the opposite wall section to provide a capacious air passage between the two, and means positively interlocking the intermeshed lugs.

12. A wall built up from molded block units and comprising inner and outer wall sections spaced apart relatively to provide an air space between them, the blocks of said outer wall section each comprising a body of refractory heat insulating material and a reinforcing metal skeleton embedded in said body and the blocks of the inner wall section being made from carborundum or the like, 80 and vertical rows of lugs upon the air spaced sides of both wall sections integral with the blocks thereof, the lugs of each vertical row of the outer wall section being alined and intermeshed with the lugs of one of the vertical rows of the inner wall section with the end of each lug of each wall section spaced away from the opposite wall section to provide a capacious air passage between the two.

13. A wall built up from molded block units comprising inner and outer wall sections spaced apart relatively to provide an air space between them, the blocks of said outer wall section each comprising a body of refractory heat insulating material and a reinforcing metal skeleton embedded therein and the blocks of the inner wall section being made from carborundum or the like; a sheet metal casing outside of said wall; a layer of heat insulating and cushioning material between 90 said sheet metal casing and said wall; anchor bolts extending through said sheet metal casing and engaging the reinforcing metal skeleton, and vertical rows of lugs upon the inner sides of both wall sections integral with the blocks 95 thereof, the lugs of each vertical row of the outer wall section being intermeshed with the lugs of one of the vertical rows of the inner wall section with the end of each lug of each wall section spaced away from the opposite wall section to provide a capacious air 100 passage between the two.

14. A refractory structure for a furnace comprising a section of refractory block units assembled with aligned longitudinally extending holes, a spaced section of refractory block units also assembled with a aligned longitudinally extending holes, and rods of refractory material removably inserted in said aligned holes and serving to lock the individual block units in place in their respective sections, and by withdrawal to permit replacement of any desired block unit.

15. A refractory structure for a furnace comprising a section of refractory block units

assembled with aligned longitudinally extending holes, a spaced section of refractory heat insulating block units, and locking rods removably inserted in the aligned holes of the refractory block units and serving to lock the individual units in place in its section, and by withdrawal to permit replacement of any desired block unit.

5 Signed by me at Boston, county of Suffolk, State of Massachusetts, this 3rd day
10 of September, 1927.
